UNITED STATES PATENT OFFICE

HANS OLOF LINDGREN, OF APPELVIKEN, SWEDEN, ASSIGNOR TO THE DE LAVAL
SEPARATOR COMPANY, OF NEW YORK, N. Y., A CORPORATION OF NEW JERSEY

CENTRIFUGAL SEPARATOR

Application filed September 18, 1930, Serial No. 432,659, and in Sweden September 28, 1929.

In centrifuges in which heavy substances, such as solids, are separated from a liquid or from a mixture of relatively heavy and light liquids and then discharged through nozzles 5 or openings located at or near the periphery of the bowl, it is common practice to introduce an "addition liquid" into the bowl at or near such openings, namely for the purpose of reducing the quantity of separated liquid 10 (of the original mixture) that discharges with the solids, and also for the purpose, in many cases, of facilitating the discharge of the solids. See British Patent No. 10,314 of 1908.

The nature of the addition liquid may vary 15 according to conditions. It is often advantageous to use, as an addition liquid, a liquid containing a greater or smaller proportion of solids similar to those which are discharged. In many cases it is convenient and desirable 20 to use, as an addition liquid, a part of the discharged product.

The feeding of such addition liquid is attended with great difficulties. The liquid must, of course, be introduced into the bowl 25 in the neighborhood of its center and be thence conducted to the neighborhood of the periphery, preferably through separate channels which avoid admixture of the addition liquid with the contents of the bowl under- 30 going separation. The channels should be so formed that they can be easily cleaned. If a mixture of liquid and solids is used as an addition liquid, sharp bends should be avoided, since a deposition of particles therein 35 easily occurs which blocks or obstructs the channels.

The present invention has for its object the provision of special means for supplying the mixture to the bowl, discharging the separated constituents, introducing the addition liquid, insuring a free flow of addition liquid, and in general increasing the efficiency of the bowl by means of a simple and inexpensive construction.

It is often highly desirable, also, to take special precautions against the mixing of the addition liquid with the liquid constituent of the original mixture. It is known to provide openings in the bowl hood into which 50 are inserted nozzles communicating with the

peripheral part of the separating space of the bowl, the openings also having orifices communicating with a collection vessel outside the bowl. Channels for addition liquid communicate with the chambers formed between said nozzles and orifices. It is possible to a limited degree to regulate the pressure of the liquid in said chambers by creating through the nozzles a directed flow of liquid sufficiently strong to prevent liquid from streaming out through the nozzles but not sufficiently strong to hinder outflow of solids or sludge through the nozzles. It is, however, extremely difficult to obtain the same pressure in the various chambers as well as to 60 introduce the addition liquid in a satisfactory manner. One of the objects of the present invention is to retain the advantages of the above described known construction and at the same time overcome the disadvantages 65 hitherto characteristic thereof.

Fig. 1 is a vertical section through a bowl embodying my invention. Fig. 2 is a similar view of another embodiment of the invention. Fig. 2 attains substantially all the objects of my invention, whereas Fig. 1 comprises only those inventive features first hereinbefore described.

Referring first to the construction of Fig. 1: The bottom *v* of the bowl is secured, by means of the lock ring *w*, to the bowl hood, which comprises a body *x* and a lining element *y* inserted in and extending above the body. The mixture to be separated is introduced into a tube *a*, which is closed at its bottom but provided with side openings *b*, through which the mixture flows into a chamber *c*. Chamber *c* is located in the upper part of the bowl hood and is provided with conveyors *d*, which force the mixture to partake 75 of the rotation of the bowl. From chamber *c* extend channels *e*, located in the upper part of the hood and through which the mixture is fed into the separator chamber of the bowl, preferably between frusto-conical discs *f*. 80

The separated heavier liquid constituent of the mixture discharges through channels *g* in the bowl hood into a chamber *h* and discharges over an exchangeable regulating disc *i*. 95

The separated lighter liquid constituent of the mixture rises through channels *j* and discharges through openings which may be provided with regulating members *k*, by means of which a more accurate regulation between the amounts of heavy liquid and light liquid can be obtained than by means of the regulating disc *i*.

If the mixture to be separated does not comprise both relatively heavy and light liquid constituents in addition to heavier substances, such as heavier solids, but comprises only such heavier substances and light liquid, only one of the described liquid outlets is provided, or at least only one is used.

The separated heavy matters, which do not discharge through channels *g* with the heavy liquid, discharge, with more or less liquid, through openings *m* arranged at or near the periphery. Openings *m* are preferably provided with nozzles of known type.

The flushing or addition liquid is introduced through a tube *n*, positioned inside and concentric with tube *a*. Tube *n* feeds into a chamber *o*. This chamber is situated in the upper portion of the hood, preferably just under chamber *c*, and is provided with conveyors *p*, which compel the addition liquid to rotate with the bowl. From chamber *o* the addition liquid flows through channels *r* in the bowl hood to the peripheral part of the bowl, preferably close to outlets *m*.

It is preferred, as hereinbefore stated, to form a complete bowl hood by inserting in the body *x* a special element *y* in which are formed the feed chamber *c* for the original mixture, the channels *e* for conveying this mixture to the separating chamber of the bowl, the feed chamber *o* for addition liquid, and preferably also the channels *r* for conveying the addition liquid to the peripheral part of the bowl, and the channels *j* for outflow of light liquid. The channels *g* for outflow of heavy liquid are preferably formed between the body *x* and the element *y* by riffling the outer side of one and/or the inner side of the other.

In the lower part of the bowl are filler pieces provided with sliding surfaces *t* to promote the flow of heavy materials to outlets *m*. These filler pieces may be fixed to or integral with the inserted element *y*.

While it is desirable to position chamber *o* over chamber *c*, this arrangement is not required.

Since the means for introducing the mixture to be separated and the outflow channels are located at the upper part of the bowl, there is ample room at the lower part of the bowl to allow it to be removably arranged on the spindle *s* which extends up within the bowl.

So far as the parts of the constructions of Figs. 1 and 2 are the same, the parts are similarly lettered.

The inserted element *y* of Fig. 2 is provided with a chamber *10*, which is preferably ring-shaped, although it need not extend continuously around the bowl. From chamber *10* extend an inner opening into the peripheral part, or sludge space, of the separating chamber of the bowl and an outer opening discharging into a collection vessel (not shown) outside the bowl. These openings are formed, preferably, in members *11* and *12*, which are insertable and removable and may be exchanged for other members having different sized openings. To the ring-shaped chamber *10* addition liquid is fed through channels *r*. Only one channel *r*, if it be of suitable dimensions, is required, but for proper distribution several such channels are desirable. There are provided special discharge channels *9*, through which addition liquid flows from the ring-shaped channel *10* to outlets controlled by regulating screws *13*. These channels may be formed, as shown, in the inserted element *y*, or may be formed between the body *x* and the element *y* by riffling the outer side of one and/or the inner side of the other, in the same manner as channels *g* of Fig. 1 are described as formed. By means of these special outflow channels *9* for addition liquid, it is possible to introduce a much larger supply of addition liquid than would otherwise be possible.

The regulating devices *i* and *k*, as well as other regulating devices, are required in order to adapt the bowl to operate satisfactorily with different mixtures to be separated and with different addition liquids. The exchangeable discs *i* permit change of radial distance, between the outlet openings for the light liquid and the outlet openings for the heavy liquid. The regulating members *k* preferably consist of turnable screws provided with eccentric holes.

It will be understood that the pressure of the liquid in chamber *10* must be determined in such manner that addition liquid is led therefrom into the separating chamber in order to prevent outflow from the separating chamber of the separated heavy liquid constituent of the original mixture. This is generally desirable in order to prevent loss of such liquid. There are, however, cases in which a small loss of separated liquid is permissible, although inflow of addition liquid into the separating space of the bowl and its admixture therein with separated liquid may be undesirable. It is, therefore, necessary to provide means for regulating the supply of addition liquid. To secure a suitable regulation of pressure in chamber *10*, the bowl is provided with the regulating devices *13* and *14*. The regulating device *14*, which may be a hollow screw, determines the inner level of liquid in chamber *o*. The pressure of liquid in chamber *10* is, however, chiefly determined by the regulating device *13*, which also may

be a hollow screw. By screwing in the device 13 the pressure in chamber 10 is increased. By screwing it out, the pressure in chamber 10 is decreased.

5 It will thus be understood that an adequate supply of addition liquid may be introduced to the bowl and that as large a proportion of such addition liquid as desired may be separately discharged from the bowl, and that the 10 heavy liquid constituent of the original mixture is separately discharged from the bowl, being prevented, to the extent desired, from admixture with the addition liquid.

It will also be understood that the pressure-regulating means described may be adjusted either to allow a slight inflow of addition liquid through nozzles 11 to prevent loss of the separated liquid constituent of the original mixture, or to allow a slight outflow of 20 such separated liquid constituent through nozzles 11 to prevent contamination with addition liquid of the separated liquid constituent that is discharged through channels g, and that it is also possible, by careful regulation of pressure, to substantially prevent flow of either addition liquid or separated liquid through nozzles 11.

Having now fully described my invention, what I claim and desire to protect by Letters 30 Patent is:

1. A centrifugal separator comprising a bowl body, a lining element within and contacting with, and having a neck extending above, the bowl body and forming therewith 35 the bowl hood, a feed chamber for the mixture to be separated formed in the neck of the lining element, and channels connecting the feed chamber with the separator space of the bowl, said lining element and channels being in fixed relation with the bowl body during operation.

2. A centrifugal separator comprising a bowl body, a lining element within and contacting with, and having a neck extending 45 above, the bowl body and forming therewith the bowl hood, a feed chamber for the mixture to be separated formed in the neck of the lining element, and channels formed in the lining element and connecting the feed 50 chamber with the separating chamber of the bowl, said lining element being in fixed relation with the bowl body during operation.

3. A centrifugal separator comprising a 55 bowl body, a lining element within and contacting with, and having a neck extending above, the bowl body and forming therewith the bowl hood, the bowl having peripheral sludge-discharge openings, means to admit 60 the mixture to be separated into the separating space of the bowl, a feed chamber for addition liquid formed in the neck of the liner element, and channels extending from the feed chamber to the peripheral part 65 of the bowl, said lining element being in

fixed relation with the bowl body during operation.

4. A centrifugal separator comprising a bowl body, a lining element within and contacting with, and having a neck extending above, the bowl body and forming therewith the bowl hood, the bowl having peripheral sludge-discharge openings, means to admit 70 the mixture to be separated into the separating space of the bowl, a feed chamber for addition liquid formed in the neck of the liner element, and substantially straight, closed channels formed in the liner element and extending from said feed chamber to the peripheral part of the bowl, said lining 75 element being in fixed relation with the bowl body during operation.

5. A centrifugal separator comprising a bowl body, a lining element within and contacting with, and having a neck extending above, the bowl body and forming therewith the bowl hood, the bowl having peripheral sludge-discharge openings, the upper part 80 of said lining element containing a feed chamber for the mixture to be separated and a feed chamber for addition liquid, channels connecting the first named feed chamber with the separating space of the bowl, and channels connecting the second named feed chamber with a peripheral part of the bowl, 85 said lining element and channels being in fixed relation with the bowl body during operation.

6. A centrifugal separator comprising a bowl body, a lining element within and contacting with, and having a neck extending above, the bowl body and forming therewith the bowl hood, the bowl having peripheral sludge-discharge openings, the upper part of 90 said lining element containing a feed chamber for the mixture to be separated and a feed chamber for addition liquid, the hood being provided with channels connecting the first named feed chamber with the separating space of the bowl, channels connecting 95 the second named feed chamber with the peripheral part of the bowl, and outflow channels for relatively heavy and light liquids, said lining element and channels being in fixed relation with the bowl body during operation.

7. A centrifugal separator comprising a bowl having a main separating space and whose wall is provided with a chamber having 100 inner openings into the sludge space of the main separating space of the bowl and outer openings to the outside of the bowl, means to feed the mixture to be separated into the separating space of the bowl, means to discharge 105 separated liquid from the separating space of the bowl, a channel adapted to convey addition liquid to said chamber, and a channel adapted to discharge addition liquid from 110 said chamber, said liquid discharging means 115 120 125 130

and channels being in fixed relation with the bowl wall during operation.

8. A centrifugal bowl having a main separating space and whose wall is provided with a ring-shaped chamber having inner openings into the sludge space of the main separating space of the bowl and outer openings to the outside of the bowl, means to feed the mixture to be separated to the separating space of the bowl, means to discharge liquid from the bowl, a feed chamber for addition liquid formed in the upper part of the bowl, and substantially straight closed feed channels connecting said feed chamber with said ring-shaped chamber, said liquid discharge means and channels being in fixed relation with the bowl during operation.

9. A centrifugal bowl having a main separating space and whose wall is provided with a peripheral chamber having inner openings into the sludge space of the main separating space of the bowl and outer openings to the outside of the bowl, means to feed the mixture to be separated to the separating space of the bowl, means to discharge liquid from the bowl, a feed chamber for addition liquid formed in the upper part of the bowl, substantially straight closed feed channels connecting said feed chamber with said peripheral chamber, and channels adapted to discharge addition liquid from said peripheral chamber, said liquid discharge means and channels being in fixed relation with the bowl during operation.

10. A centrifugal separator comprising a bowl body having a main separating space and a lining element within and contacting with the bowl body and forming therewith the bowl hood, means to feed the mixture to be separated into the separator space of the bowl, means to discharge liquid from the separator space of the bowl, a chamber formed in the lining element, there being inner openings from said chamber into the sludge space of the bowl and outer openings from said chamber through the bowl body, and means to supply an addition liquid to said chamber, said lining element and liquid discharge means being in fixed relation with the bowl body during operation.

11. A centrifugal separator comprising a bowl body having a main separating space and a lining element within and contacting with the bowl body and forming therewith the bowl hood, means to feed the mixture to be separated into the separator space of the bowl, means to discharge liquid from the separator space of the bowl, a chamber formed in the lining element, there being inner openings from said chamber into the sludge space of the bowl and outer openings from said chamber through the bowl body, means to supply an addition liquid to said chamber, and means to discharge addition liquid from said chamber, said lining element and liquid

discharge means being in fixed relation with the bowl body during operation.

12. A centrifugal bowl provided with a channel for supplying the mixture to be separated to the separating space of the bowl, an outflow channel for separated liquid, peripheral sludge-discharge openings in series, a channel for supplying addition liquid to the peripheral part of the bowl between the sludge discharge openings, pressure regulating ports relatively near the axis of the bowl, and a channel for discharging addition liquid from the peripheral part of the bowl through said pressure regulating ports.

13. A centrifugal separator comprising a bowl having a main separating space and whose wall is provided with a chamber having openings into the sludge space of the main separating space of the bowl and openings to the outside of the bowl, means to feed the mixture to be separated into the separating space of the bowl, means to discharge separated liquid from the separating space of the bowl, a channel adapted to convey addition liquid to said chamber, a channel adapted to discharge addition liquid from said chamber, and adjustable means to continuously and uniformly regulate the pressure in said chamber.

14. A centrifugal separator comprising a bowl having a main separating space and whose wall is provided with a chamber having openings into the sludge space of the main separating space of the bowl and openings to the outside of the bowl, means to feed the mixture to be separated into the separating space of the bowl, means to discharge separated liquid from the separating space of the bowl, a channel adapted to convey addition liquid to said chamber, a channel independent of said openings, adapted to discharge addition liquid from said chamber, and a constantly open regulating device controlling the outlet from the last named channel and adapted to continuously and uniformly regulate the pressure in said chamber.

15. A centrifugal separator comprising a bowl body having a main separating space and a lining element within and contacting with the bowl body and forming therewith a bowl hood, and separate channels for conveying the mixture to be separated into the separating space of the bowl and an addition liquid to the peripheral part of the bowl, said channels having walls formed by said lining element, said lining element being in fixed relation with the bowl body during operation.

In testimony of which invention, I have hereunto set my hand, at Stockholm, Sweden, on this 29th day of August, 1930.

HANS OLOF LINDGREN.
